Caleb S. Gurney
By his Attorney,

J. C. Somes

UNITED STATES PATENT OFFICE.

CALEB S. GURNEY, OF KENNEBUNK, MAINE.

DESIGN FOR A BUSINESS-CERTIFICATE.

SPECIFICATION forming part of Design No. 18,247, dated April 10, 1888.

Application filed November 19, 1887. Serial No. 255,675. Term of patent 3½ years.

To all whom it may concern:

Be it known that I, CALEB S. GURNEY, a citizen of the United States, residing at Kennebunk, in the county of York and State of Maine, have invented and produced a new and original Design for Advertising-Cards, of which the following is a specification, reference being had to the accompanying drawings, forming a part hereof, wherein—

10 Figure 1 is a view of the face of the card, and Fig. 2 is a view of the back thereof.

15 The leading features of the face of my design consist in a centrally-disposed cut, picture, or engraving representing commerce, such picture being surrounded by a suitable border, a blank for the number, a space for the amount, and suitable spaces for printing in other matter.

20 The leading features of the back of my design consist in three circles—one large one at the center for containing any printed matter desired, and one smaller one at each side thereof for the amount—the circles being each surrounded by a border, and the whole otherwise unoccupied space on the back being filled in with ornamental scroll-work, substantially as illustrated.

25 In the drawings, Fig. 1, A is the cut representing commerce, surrounded by a circular border, B, of two concentric rings, a set 30 of dark triangles, b, surrounding the outer ring, like the points on a serrate leaf, and a second set of larger outline triangles, b', surrounding the triangles b, and their points alternating therewith. This cut is preferably disposed a trifle below the center of the sheet.

35 O is a blank for the amount, such blank being disposed in the upper right-hand corner, and surrounded by a border of two parallel lines 40 forming two similar inward scallops, c, on each side and in vertical alignment, and a pair of similar scallops, c', from each of the upper and lower ends of the sides, inclined inward and meeting at top and bottom points, the latter being ornamented by any suitable filigree.

45 D is a space for the number, preferably disposed at the lower left-hand corner.

50 d represents a horizontal rod or roller having acorns at its ends, from which roller falls in a graceful curve a tinted sheet, d', its sides widening toward the lower edge and being

represented as rolled back and up, showing the corners at d'. The face of the sheet d' carries the abbreviation "No.," followed by a space for figures.

55 E is a small oblong space at the center, near the upper edge, surrounded by a double-line border, the end curves having extensions of such double lines in small loops of U shape, substantially as shown.

60 F is a large vertical oval at the left, above the space for the number, surrounded by a scroll filigree of any desired character. This space may contain any matter desired, or, in fact, may be dispensed with entirely, if preferred.

65 G represents a lateral ribbon extending across the card near the top, its right end being folded down and back at g to give space for the amount-blank O, and its left end being folded up and back at g' before it reaches the left edge of the printing or engraving. If the oval F is used, this ribbon is broken away over the space occupied thereby, thus giving it the appearance of extending behind such oval. The face of the ribbon G is suitably tinted, and near each backward fold a small scroll, leaf, or other ornamental design is engraved thereon to give it a finished appearance.

70 The entire face of the card is surrounded by a narrow border comprising a double line, h, a series of equilateral triangles, h', resting thereon and pointing toward the center, a single line along their points, shading h' between them, thus forming an alternating row of outline triangles, h', and shaded triangles h'', the points of all such angles being solid, as at h''. The corners h' are preferably small squares containing a central dot.

75 Referring again to the drawings, Fig. 2, I represents the central large circle, which is surrounded by a border of two concentric lines, preferably about one-quarter of an inch apart, between which is a series of interlaced or interlapping small circles, i, whereof three 80 on either side of any given one have a segment within that one, such segment coming in contact with that of the opposing circle on the opposite side; or, in other words, a set of touching circles is first drawn, a second 85 set next drawn whose centers are on the meet-

ing points of the first set, and finally a third set is drawn whose centers are midway between the centers of the first two sets. Around the outer circle is a set of double-line scallops, i' , whose points touch such outer circle, these scallops being broken away at top and bottom near the border and scroll-work filled in for ornamentation. Still outside of the scallops, on either side of the circle I , is a large double-line curve, i' , concentric with the border-circles, whose ends are angled and led away to either side parallel with the edge of the card, being provided with an inwardly-extending spiral, i' , and with rings i' , or other ornamental end tips.

J J are the smaller amount circles, one on either side of the circle I , and disposed at the geometric centers between such large circle and the ends of the card. These small circles are alike, and a description of one will suffice for both: a border comprising two concentric double-line rings, j , preferably about one-fourth of an inch apart, between which, at top and bottom and at each side, is a small oval, j' , having a dot center. Disposed between these ovals j' are lines and dots, substantially as illustrated. Outside the outer ring is a double-line ring, j' , open at top and bottom and at the sides, where the ends curve spirally outward, and between such spiral

ends are filigree figures for further ornamentations.

The entire back is surrounded by a border, K , of a heavy line and two light lines. At each corner is a fan, L , having a shaded body 35 and light blades or panels, l , and a scalloped edge, l' , and a plain light point, l'' . Inside the large border K is a double line, M , parallel therewith, but following the curved inner edge of the corners L , as at m , while near the 40 center, at top and bottom, it is merged into the scroll-work of the scallops i' . The ground-work N , outside of the three circles, the corners, and the several figures, is preferably tinted a separate and distinctive color. 45

I claim—

1. The design for a business-card having obverse and reverse sides, substantially as herein shown and described.
2. In the design for a business-card, the 50 design for the obverse, substantially as herein shown and described.
3. In the design for a business card, the design for the reverse, substantially as herein shown and described.

CALEB S. GURNEY.
